FLOAT

Edward F. Rupp, Cleveland, Ohio

Application January 25, 1943, Serial No. 474,250

6 Claims. (Cl. 271—89)

This invention relates to a float to be applied to the jogger of a printing press and it is an object of the invention to provide a device of this kind which provides a box having a wall constructed to allow escape of air to facilitate even drop of the printed matter from the delivery end of a press into the box.

It is also an object of the invention to provide a device of this kind wherein the escape of air from the box formed thereby may be varied or adjusted to accommodate the different weights of paper used in the printing process.

The invention consists in the details of construction and in the combination and arrangement of the several parts of my improved spray float whereby certain important advantages are attained, as will be hereinafter more fully set forth.

In order that my invention may be the better understood I will now proceed to describe the same with reference to the accompanying drawing, wherein

Figure 1 is a view in top plan illustrating a float constructed in accordance with an embodiment of my invention and in applied position upon a jogger;

Figure 2 is an enlarged detailed sectional view taken substantially on the line 2—2 of Figure 1 the parts beyond the section line being omitted.

Figure 3 is an enlarged detailed sectional view taken substantially on the line 3—3 of Figure 1;

Figure 4 is an enlarged detailed sectional view taken substantially on the line 4—4 of Figure 1;

Figure 5 is an enlarged detailed sectional view taken substantially on the line 5—5 of Figure 1; and

Figure 6 is a view in perspective of my improved float assembled but unapplied.

In the accompanying drawing, A denotes the operating members of the jogger mechanism which are reciprocated in a well known manner from the printing press proper, and mounted upon these members A are the side boards 1, the rear bar or rail 2 and the front bar or rail 3. The front bar or rail 3 at its extremities is provided with the sleeves a through which the members A are freely directed, thus allowing the bar 3 to be adjusted lengthwise of the members A. The bar 3 is maintained in desired adjusted position by the usual clamping screws b.

Interposed between the bars or rails 2 and 3 are the side boards 1. Each of these boards 1 is provided with a rearwardly disposed arm c which is adjustably connected, as at d, with a forwardly directed arm e carried by the adjacent

member A. This particular mounting for each of the side boards allows the same to be adjusted within certain limits with respect to the opposed side board. The adjustments of the side boards 1 and the bar 3 are determined by the size of the sheet delivered from the press.

The jogger mechanism in its operation or detailed construction forms no particular part of my invention other than as a supporting means for the float, as particularly illustrated in Figure 6 of the drawing. This float in its assembly is supported by the side boards 1 and the members or rails 2 and 3 of the jogger mechanism and the float embodies a structure to allow the same to be readily adjusted in accordance with the size of the paper used in the printing process, and as delivered from the printing press. The float serves to provide an effective means whereby is prevented any off-set of the ink on the sheets delivered to the pile. By off-set is meant smearing of the ink on the back of the printed sheet.

The various parts of my improved float are formed of sheet metal of requisite weight and the float comprises an elongated front plate 4 having its upper portion a outwardly offset at 5, this off-set portion 5 extending from end to end of the plate 4 and being disposed on an upward and outward predetermined angle. The plate 4 is of considerable length and has its upper marginal portion defined by an outwardly disposed flange 6 at right angles to the portion a of the plate 4. The outer longitudinal marginal portion of the flange 6 is defined by a depending flange 7, this flange 7 co-acting with the adjacent portion a of the plate to provide a downwardly facing groove 8 in which is snugly received the upper end portions of the upstanding posts 9 carried by the member or rail 3. The upper portion a of the plate has direct contact with these posts 9, thereby assuring the plate 4 to be effectively suspended in desired working position.

The float also comprises an elongated back plate 10 of a length substantially co-extensive in length with the plate 4. This plate 10 is also of a height approximately the same as the height of the portion of the plate 4 below the offset portion 5 thereof. The upper marginal portion of the plate 10 has disposed therealong the outwardly directed and perpendicularly related flange 11. The outer longitudinal margin of this flange 11 is provided therealong with a depending flange 12. This flange 12 coacts with the upper portion of the plate 10 to provide a groove or channel 14 to receive the upper portions

of the posts, one of which being shown at 15 in Figure 3, carried by the member or rail 2 at desired points spaced therealong. By this means the plate 10 is suspended in desired position. The lower portion of the plate 10 is provided therealong and adjacent to its bottom edge with a plurality of outstanding flanges 16, the outer portions of which being returned, as at 17, whereby are provided guide grooves 18 for the outstanding flanges 19 carried by the lower marginal portion of a slide 20. This slide 20 has close contact with the outer face of the plate 10 and is provided at its upper margin with an outwardly disposed flange 21 which closely contacts from below with the flange 11 of the plate 10, as is clearly illustrated in Figure 3. This flange 21 also has close contact with the flange 12. It will, therefore, be noted that the slide 20 is effectively maintained in position with respect to the plate 10, yet free to have endwise sliding movement along said plate 10.

The slide 20 is of a substantial length and is provided therealong with the longitudinally spaced openings 22, these openings 22 in the present embodiment of the invention being relatively large and being adapted to be brought into full or partial register with the openings 23 provided in the plate 10. The openings 23 are spaced apart to the same extent as the openings 22. The side members of the float each comprises two sections 24 and 25, the upper marginal portions of these sections being provided therealong with the outwardly disposed flanges 26 terminating in the depending flanges 27. The flange 26 of one of the sections is of a greater width than the flange 26 of its associated section to allow the flanges 26 and 27 of one section, as 24, to telescopically engage within the channel formed by the flanges 26 and 27 of the second section 25. It will, therefore, be obvious that the sections 24 and 25 may be adjusted endwise one with respect to the other. It is also believed to be pointed out that the flanges 26 of the sections of the side members engage from above the side members 1 of the jogger mechanism and are thereby effectively suspended in desired position.

To further maintain the side members in desired assembly the forward end of each of the outer sections 25 has its flange 26 provided with a forwardly or outwardly directed hook member 28 which snugly engages over the flange 11 of the plate 10. In view of the foregoing it is believed to be readily apparent that the side sections of the float may be readily adjusted one toward the other, as may also be the plates 4 and 10 so that the float will have the same requisite adjustment as the jogger mechanism, as determined by the size of the printed sheets delivered from the press. It is also believed to be obvious that as the sheets drop upon the pile and within the float the requisite positioning of the sheets will be facilitated by contact of the rear margins of the sheets with the off-set portion 5 of the rear plate 4.

As the sheet drops within the float the air therebeneath will allow the sheet to drop even. The openings 22 permit escape of air under the paper as it falls and thereby permits the paper to fall faster in the back or rear portion of the float on account of the lowering of the air resistance as the air escapes out through such openings.

One end portion of the slide 20 is provided with an outstanding bracket 29 to provide means to facilitate the desired moving of the slide 20.

From the foregoing description it is thought to

be obvious that a float constructed in accordance with my invention is particularly well adapted for use by reason of the convenience and facility with which it may be assembled and operated.

5 I claim:

1. A float for use in connection with a jogger mechanism of a printing press including operating members, front and rear bars carried by the operating members, and side boards carried by said members; said float comprising a rear plate, channel means carried by said plate for engagement over and along the rear bar of the jogger mechanism, a front plate, channel means for engagement over and along the front bar of the jogger mechanism, side plates, means carried by the side plates for supporting the same upon the side boards of the jogger mechanism between the front and rear plates of the float, one of the plates being provided with air openings, and means for regulating the flow through said openings.

10 2. A float for use in connection with a jogger mechanism of a printing press, including front and rear bars carried by the operating members, and side boards carried by said members; said float comprising a rear plate, channel means carried by said plate for engagement over and along the rear bar of the jogger mechanism, a front plate, channel means for engagement over and along the front bar of the jogger mechanism, side plates, means carried by the side plates for supporting the same upon the side boards of the jogger mechanism between the front and rear plates of the float, one of the plates being provided with air openings, and a slide carried by the 15 plate having the openings, said slide having openings to be brought wholly or partially into register with the openings in the plate.

20 3. A float for use in connection with a jogger mechanism of a printing press, including front and rear bars carried by the operating members, and side boards carried by said members; said float comprising a rear plate, channel means carried by said plate for engagement over and along the rear bar of the jogger mechanism, a front plate, channel means for engagement over and along the front bar of the jogger mechanism, side plates, means carried by the side plates for supporting the same upon the side boards of the jogger mechanism between the front and rear plates of the float, one of the plates being provided with air openings, means for regulating the flow through said openings, and means carried by the side plates for detachable holding engagement with one of the first-named plates.

25 4. A float for use in connection with a jogger mechanism of a printing press, including front and rear bars carried by the operating members, and side boards carried by said members; said float comprising a rear plate, channel means carried by said plate for engagement over and along the rear bar of the jogger mechanism, a front plate, channel means for engagement over and along the front bar of the jogger mechanism, side plates, means carried by the side plates for supporting the same upon the side boards of the jogger mechanism between the front and rear plates of the float, one of the plates being provided with air openings, and means for regulating the flow through said openings, the side plates being free 30 for movement along the front and rear plates, said side plates each comprising a plurality of sections adjustable lengthwise one with respect to the other.

35 5. A float for use in connection with the jogger mechanism of a printing press, including front

and rear bars carried by the operating members, and side boards carried by said members; said float comprising a rear plate having a portion of its top edge formed to provide a downwardly opening channel for engagement over and along the rear bar of the jogger mechanism for the hanging support of the plate, a front plate having a portion of its top edge formed to provide a downwardly opening channel adapted for engagement over and along the front bar of the jogger mechanism for the hanging support of the front plate, side plates connected between the front and rear plates, means forming a part of the side plates for the engagement of the same with and the support of the same from the side boards of the jogger mechanism, one of said first mentioned plates having air openings therein, means forming a guide longitudinally of the outer face of the said

one of the first mentioned plates beneath the air openings, and a side plate having openings corresponding with the openings of the said one of the first mentioned plates and positioned against the outer side of the said one of the first mentioned plates between the guide flange and channel, the slide having outwardly extending longitudinal edge portions one of which is slidably engaged in the adjacent channel and the other of which is slidably engaged in the guide means.

5 6. A float as described in claim 5, in which said side plates are each formed in two sections telescopically joined together, the top portion of each of the two sections of each side plate being formed to provide a longitudinal downwardly opening channel for the reception of the top edge of a side board.

EDWARD F. RUPP.
